UNITED STATES PATENT OFFICE.

CARL BRUNO DREVITSON, OF SOMERVILLE, MASSACHUSETTS.

CONNECTING ROD.

Application filed December 8, 1921. Serial No. 520,887.

To all whom it may concern:

Be it known that I, CARL B. DREVITSON, a citizen of the United States, residing at Somerville, in the county of Middlesex and 5 State of Massachusetts, have invented new and useful Improvements in Connecting Rods, of which the following is a specification.

This invention relates to a connecting-rod 10 pivotally connected at its outer end to a piston in the combustion cylinder of an internal combustion engine, and connected at its inner end with a bearing surrounding the wrist portion of a crank-shaft.

15 The object of the invention is to provide a connecting-rod of simple and durable construction, adapted to yieldingly cushion the direct blow on the crank-shaft caused by the combustion or explosion of a charge of gaseous material in the cylinder, in such manner as to reduce wear on the bearing, and 20 eliminate shocks or jars, so that the engine will run quietly and smoothly.

The invention is embodied in the improvements hereinafter described and claimed.

Of the accompanying drawings forming a part of this specification,—

Figure 1 is a view showing in section a piston and a portion of a crank-shaft, and 30 partly in elevation, and partly in section, a connecting-rod embodying the invention.

Figure 2 is a section on line 2—2 of Figure 1.

Figure 3 is a section on line 3—3 of Figure 1.

Figure 4 is a fragmentary perspective view, showing portions of the connecting-rod and bearing, said portions being connected.

40 The same reference characters indicate the same parts in all of the figures.

My improved connecting-rod is adapted to connect the piston 12 and the wrist 13 of the crank-shaft of an internal combustion engine, the rod being pivotally connected at 45 one end with the piston, and provided at the opposite end with a bearing surrounding the wrist 13.

The connecting-rod includes an elongated 50 rigid body 14, preferably formed in cross section, as shown by Figure 2, and provided at one end with a rigid member 15, forming an element of the usual, or any suitable one-point pivotal connection between the rod 55 and the piston, permitting the rod to oscil-

late as usual, and conform to the revolving movement of the crank-shaft wrist.

The body 14 is provided at its opposite end with means forming a resilient two-point connection between the body and the 60 crank-shaft bearing, adapted to yield sufficiently to cushion the blow or abrupt pressure on the bearing and crank-shaft, caused by the combustion of a gaseous working agent in the cylinder containing the piston. 65 Said two-point connection is preferably provided by forming on the inner end of the body 14, two extensions 16, which are integral with the body, and constitute elbow-shaped springs, rigidly connected at their 70 outer ends with the ears 17 on a part or member 19 of a two-part bearing. The connecting-rod is, therefore, bifurcated at its inner ends, its furcations being resilient. The said extensions and the said bearing 75 member may be rigidly connected in any suitable way. For example, the extensions may be formed integral with the bearing member by a drop-forging operation, the body 17, its extensions, and the bearing member 80 and its ears being formed as a single piece or forging.

The form of the two-point connecting means and the body 14 is such that the bearing member 19 is separated from the inner 85 end of the body by a space or recess 21, which receives a portion of the bearing, and permits an independent endwise movement of the body 19, without contact of its inner end with the bearing, said recess extending 90 across the bearing, so that the body 14 is connected with the bearing at two points, one at each side of the axis of the bearing.

A blow or shock on the piston is therefore 95 yieldingly transmitted to the bearing and the crank-shaft by two springs, one at each side of the longitudinal center of the body 14, so that the strain is distributed between the springs, and liability of the setting of the springs is avoided.

100 The crank-shaft bearing may include a member 22 complementary to the member 19, the members being detachably connected as by bolts 23.

I claim:

1. A connecting-rod comprising an elongated rigid body, having at one end a rigid member forming an element of a one-point pivotal connection between said body and a piston; and at its opposite end a crank- 110

shaft bearing member, and means forming a resilient two-point connection between the body and the said member, said means being integral with the body and the bearing member, and adapted to space the body from the bearing member.

2. A connecting-rod comprising an elongated rigid body, having at one end a rigid member forming an element of a one-point pivotal connection between said body and a piston; and at its opposite end a crank-shaft bearing member and a pair of oppositely projecting resilient extensions forming a resilient two-point connection between said body and bearing member, and adapted to space the body from said member, said bearing member and extensions being integral with the body.

3. A connecting-rod comprising an elongated rigid body, having at one end a rigid member forming an element of a one-point pivotal connection between said body and a piston, the opposite end of said body having a crank-shaft bearing member and resilient means forming, with the body, a recess adapted to receive a portion of said bearing member, said resilient means forming a two-point connection between the body and the bearing member, and adapted to space the body from said member, said bearing member and resilient means being integral with the body.

4. A one-piece connecting-rod comprising an elongated rigid body, having at one end an integral member forming an element of a one-point pivotal connection between said body and a piston; and having at the opposite end, integral resilient means forming a resilient two-point connection between the body and a crank-shaft bearing, and forming, with the body, a recess adapted to receive a portion of the bearing, said two-point connection being adapted to space the body from the bearing.

45 5. A connecting-rod comprising an elongated rigid body portion, and a bifurcated lower end portion, the furcations of which are resilient, and form a resilient two-point connection between the body portion and a crank-shaft bearing, adapted to space the body portion from the bearing, the opposite end of the body portion having a rigid member forming an element of a one-point pivotal connection between the body portion and a piston.

50 55 6. In a connecting-rod, in combination, a crank-shaft bearing, and an elongated rigid rod body, having at one end a rigid member forming an element of a one-point pivotal connection between the body and a piston, and at its opposite end means resiliently connecting the body with the bearing at two points, one at each side of the bearing, said means spacing the body from the bearing.

65 7. In a connecting-rod, in combination, a crank-shaft bearing, and an elongated rigid rod body, having at one end a rigid member forming an element of a one-point pivotal connection between the body and a piston, and at its opposite end a pair of 70 oppositely projecting resilient extensions, forming a resilient two-point connection between the body and the bearing, and spacing the body from the bearing.

75 8. In a connecting-rod, in combination, a crank-shaft bearing, and an elongated rigid rod body, having at one end a rigid member forming an element of a one-point pivotal connection between the body and a piston, and at its opposite end a pair of 80 oppositely projecting resilient extensions, forming a resilient two-point connection between the body with the bearing, and spacing the body from the bearing, said extensions forming with the body a recess receiving a portion of the bearing, and spacing the body from the bearing.

85 In testimony whereof I have affixed my signature.

CARL BRUNO DREVITSON.
